PACKING SEGREGATED UNITS

Raymond A. Waldron, West Chester, Victor F. Leto, Kennett Square, and Louis Lescarboura, Oxford, Pa.

Application February 3, 1932. Serial No. 590,556

2 Claims. (Cl. 217—122)

Our invention relates to packing segregated units. The object is to provide improved means for packing segregated units-by-weight of certain products, such as mushrooms, in a common container, so that any said unit may be removed from the common container without disturbing other units.

The invention comprises improved means for fitting the units in a common container and improved means for facilitating the removal of one or more units from said container. The respective units may be of any required character with respect to weight or bulk.

It has become common practice among mushroom growers to pack and ship mushrooms in baskets or containers holding about three pounds.

The basket adopted by mushroom growers and dealers has become standard as to capacity and shape.

It is oblong, having curved ends and substantially straight sides. The sides and ends however taper or converge from the top to the bottom.

The method of merchandising by means of such container has proved to have certain objections.

It happens frequently that a customer desires to purchase an amount less than the total content of the basket, so that this amount must be removed from the container containing, say, three pounds in bulk.

In removing a portion of the bulk, the original packing is disturbed, the individual mushrooms are often broken or bruised, and when it is attempted to remove one or two pounds from said bulk, it often happens that the remaining bulk does not weigh the expected one or two pounds, moreover, in the handling and removing said portion, or portions, the remaining bulk does not contain the uniform size and quality averaged in the original bulk.

The object therefore of the present invention is to overcome these objections by segregating the total bulk contained in the basket, into units-by-weight so that the desired unit or units may be removed from the basket to satisfy the particular customer's need, without disturbing the balance of the basket's contents.

Since the character of the basket has become standard for the particular class of merchandise, that is mushrooms, and since it would be extremely difficult and expensive to introduce any different type of basket for this purpose, it has been found desirable to provide such segregating means as shall conform to the exact shape

and size of said basket, so that the same shall pack precisely within said basket, and so that, at the same time, a separate unit may be readily removed from the basket without disturbing the remaining units.

Referring to the drawing which illustrates, merely by way of example, suitable means for effecting the invention;—

Fig. 1 is a view in perspective of the basket having the separate unit containers but with the lid removed.

Fig. 2 is a longitudinal section on line 2, 2 of Fig. 1, with the lid in place.

Fig. 3 is a cross-section on line 3, 3 of Fig. 1, also with the lid.

Fig. 4 is a perspective view of an end container.

Fig. 5 is a similar view of a middle container.

Similar numerals refer to similar parts throughout the several views.

It will be noted that the basket 7 is oblong with its side walls straight and parallel and its end walls curved, in the planes of its horizontal section.

These side and end walls however converge or taper downwardly, so that the maximum dimensions of its opening at the top are, for example, approximately six by fourteen inches and its inside bottom dimensions are approximately four by twelve inches.

This basket is adapted to contain, in the present example, about three pounds of mushrooms. In order to secure the segregation by units of weight, as above described, three sub-containers or boxes are provided as indicated by 8, 9 and 10. The boxes 8 and 10 are adapted to fit in the basket ends, each having one straight wall 11 and the opposite partly curved wall 12. The wall 11 is not only straight, but is preferably perpendicular to the bottom 13 of the basket. The adjacent flanking side wall extensions 14 are straight but inclined to said bottom. These wall extensions 14 are developed into the curved wall 12. Wall 12 is not only inclined to the plane of the bottom but is in form corresponding to a side fragment of a funnel.

The middle box 9 has its two walls 15, which are adjacent the walls 11 of the end boxes, are parallel to said walls 11. The two walls 16 adjacent the side walls of the basket are straight and parallel with said side walls, and thus taper toward and are inclined to the bottom, as indicated in Fig. 3.

By this arrangement the several sub-boxes or containers fit snugly together, within the surrounding walls of the basket, their weight con-

105

110

tributing to the snug fit. Because of the tapered conformation of the boxes and of the correspondingly tapered surrounding walls of the basket, the said boxes are very easily assembled, separated and removed.

It will be understood that the side walls of the basket may extend slightly above the side walls of the sub-boxes if desired.

What we claim is:—

- 10 1. A mercantile unit for packaging mushrooms comprising an outer container of conventional form and a plurality of sub-containers fitted therein in such manner as to occupy the aggregate content of the outer container and to provide an aggregate content of the sub-containers substantially equal to the bulk content of the outer container, each sub-container being so positioned and so shaped as to be independently re-
- 15

movable without disturbing the other sub-containers.

2. A mercantile unit for packaging mushrooms comprising an outer container of conventional form having side walls partly straight and partly curved in horizontal section and converging toward the bottom wall and a plurality of sub-containers fitted therein in such manner as to occupy the aggregate content of the outer container and to provide an aggregate content of the sub-containers substantially equal to the bulk content of the outer container, each sub-container being so positioned and so shaped as to be independently removable without disturbing the other sub-containers.
